UNITED STATES PATENT OFFICE.

HAROLD V. McCORMICK, OF LONG BEACH, NEW YORK, ASSIGNOR, BY MESNE ASSIGNMENTS, TO SHUR-LOC ELEVATOR SAFETY CORPORATION, OF NEWARK, NEW JERSEY, A CORPORATION OF NEW JERSEY.

ELEVATOR.

Application filed November 26, 1926. Serial No. 150,700.

In an application of Thomas S. Harrison, Serial No. 98,995, filed April 1, 1926, and in an application of John Darby, Serial No. 139,603, filed October 5, 1926, both assigned 5 to the Shur Loc Elevator Safety Company, the assignee herein, there are shown and described interlocking safety devices in which the opening of the shaft door, when the car is at the floor level, causes the controller 10 locking rod to be held in engagement with the controller so that the controller cannot be moved to start the car from the floor in either direction and in which the door cannot receive its full opening movement unless the 15 car is at the corresponding floor level and in a position, by reason of a part carried by it, to offer resistance to a moving part which is necessary to release for full movement the door and parts associated with it. In the embodiment of the inventions shown in both of 20 said applications, the door, in its closed position, is in engagement with a forked lever mounted on the sill and in the beginning of the movement of the door swung from its 25 initial position to a position in which it releases the door for full movement and such forked lever is operatively connected with a part which moves with the lever in the initial movement of the door and is held from 30 movement by the engagement therewith of a locking device so that the forked lever cannot have its releasing movement and the door cannot be opened unless the car is at the floor and in position to effect the disengagement 35 of such locking device. In the operation of elevators there sometimes happens an emergency in which it is necessary to open the shaft door when the car is not in position at the floor and therefore does not effect the 40 release of the locking device which prevents full opening movement of the door and in the application of John Darby, above mentioned, there is shown and described and claimed broadly an emergency release device, by the operation of which from the hall, that is from the side of the door and elevator casing remote from the car, it is possible to disengage the locking device and permit the door to be opened. The present invention 45 relates to means whereby, under such circumstances, the door can be released for opening and its purpose is to provide a different and in some installations perhaps a preferable form of emergency release directly related

operatively to the forked lever above mentioned. 55

The invention will be more fully explained hereinafter with reference to the accompanying drawings in which it is illustrated and in which: 60

Figure 1 is a view, as seen from above, showing a portion of a shaft door, a portion of an elevator car with its controller connections and the interlocking devices, substantially as shown in Figure 1 of the drawings 65 of the application of John Darby, above mentioned, but with the improved emergency release which forms the subject of the present invention, the shaft door and associated parts being shown in the positions which 70 they assume when the door is closed.

Figure 2 is a view of the same in elevation, as seen from the right-hand in Figure 1, with the wall of the car removed, the notched controller and the controller rod with its operative connections being also shown, all substantially as in Figure 2 of the drawings of 75 the said application of John Darby.

Figure 3 is a detail view in elevation showing the application of the improved emergency release to the forked lever. 80

Figure 4 is a view of the parts shown in Figure 3, as seen from the left-hand in Figure 3, with the door shown in vertical section. 85

Figure 5 is a top view of the parts shown in Figures 3 and 4, with the door in horizontal section.

The improved emergency release is shown 90 in operative relation with one member *a* of a two-part or two-speed shaft door, but it will be understood that such device may operate in the same manner whether the door is a single door or is made up of several members. 95

In a suitable bracket *b* secured to each floor in proximity to the rear edge of the door *a*, when in its closed position, is mounted a forked lever *c* for engagement with the roller bearing stud *a²* carried by 100 the door *a*. In the closed position of the door, the forked lever stands in the position shown by full lines in Figure 3, and as the effective opening movement of the door begins, the lever *c* is swung from the full line 105 position to the successive positions indicated by broken lines, the stud, in the extended movement of the door, passing over and be-

yond the right-hand member of the forked lever. Connected with the lever c (but indirectly in the present case), is a connecting rod d which, at its other end, is operatively connected, as through a bell crank lever d^1 , with a slide e mounted in a guide e^1 on the door sill or floor and carrying a dog f , which is held normally by a light spring f^1 , or by its own weight, in position to engage a fixed shoulder e^2 on the guide housing e^1 , the dog f , when in engagement with the shoulder, preventing the full sliding movement of the slide e , and therefore the effective opening movement of the door, which is connected 15 with the slide through the forked lever c , as already described.

All of the parts thus far referred to are arranged and operate substantially as shown and described in said application of John Darby and the dog f is disengaged from the stop to permit movement of the slide e and therefore movement of the forked lever c and the release of the door for full opening movement, as fully described in said application 20 of John Darby. These devices form no part of the present invention and therefore need not be described in detail herein, it being sufficient to say that so long as the dog f is in engagement with the stop, the slide can- 25 not be moved and the forked lever cannot be moved to release the door unless it is itself released. It is with the devices for effecting such release of the forked lever and therefore permitting the full opening of the door when 30 the car is not at the floor and the opening of the door would otherwise be prevented, that the present invention is particularly concerned.

As shown particularly in Figures 3, 4 and 40 5, the forked lever c is mounted on a fixed stud c^3 , but is not itself directly connected with the connecting rod d . On the same axis with the lever c is mounted a locking member c^4 , which has the rod d connected 45 therewith, as at c^2 . The locking member c^4 is adapted to be connected with the lever c to move therewith and to be disconnected therefrom in an emergency. As shown, the member C^4 , is notched, as at c^2 , for engage-

ment with a latch c^6 , which is hung on the 50 lever c and is held normally in engagement with the locking member c^4 by a spring c^7 .

In the door a , in position adjacent to the forked lever, when the door is closed, is formed an opening a^1 through which can be 55 introduced a suitable implement, such as a rod a^2 , by which, from the side remote from the forked lever, it is possible in an emergency to disengage the latch c^6 from the member c^4 and therefore to permit the forked lever c to be moved independently of the member c^4 , which may then be held from movement by the locking device f in coaction with the slide e .

It will be understood that various changes 60 can be made in the construction shown to suit different conditions of use and that the invention is not restricted to the particular construction shown and described herein, except as may be pointed out in the claims. 70

I claim as my invention:

1. In an elevator, the combination of a 75 movable door, a forked lever engaged by the door in its closed position and adapted to swing to release the door, a locking member normally movable with the forked lever, a locking device to prevent movement of such locking member, and a releasable connection between the forked lever and the locking member operable to release the forked lever for independent movement when the locking member is locked against movement.

2. In an elevator, the combination of a 80 movable door, a forked lever engaged by the door in its closed position and adapted to swing to release the door, a locking member pivoted coaxially with the forked lever, a locking device to prevent movement of such locking member, and a latch normally connecting the forked lever and the locking member and disengageable to permit independent movement of the forked lever when the locking member is locked against movement. 90

This specification signed this 23rd day of November A. D. 1926. 95

HAROLD V. McCORMICK.
